BRASSIÈRE

Agnes A. Clark, Englewood, N. J.

Application August 9, 1940, Serial No. 351,941

3 Claims. (Cl. 2—42)

My invention relates to a garment of the brassière type.

It is a known fact that many ills of or attributable to the breasts are caused by unnatural pressures applied to the breasts by various types of brassières, corselettes and similar garments.

It is an object of the invention to provide an improved form of brassière which will adequately support the breasts without harmful pressures thereon.

A more specific object is to provide a brassière with means for supporting the breasts from beneath and without undue pressures.

Another object is to provide a brassière so formed as to provide a breast pocket having a generally horizontally extending lower breast supporting portion.

It is another object to provide a brassière having breast pockets having an extensible portion therein for adequately yet comfortably supporting the breasts.

Another object is to provide a brassière having breast pockets with stiffened supporting portions at the lower side for supporting the breasts adjacent the body.

In general the object is to provide an improved form of brassière for adequately, comfortably and safely supporting the breasts, particularly very heavy breasts.

In the drawing which shows, for illustrative purposes only, a preferred form of the invention—

Fig. 1 is a side view in elevation of a brassière applied to the body and illustrating features of the invention;

Fig. 2 is a front view in elevation of the brassière shown in Fig. 1;

Fig. 3 is an enlarged fragmentary sectional view of the brassière not applied; and

Fig. 4 is a view similar to Fig. 3 but showing the brassière applied to the body.

The invention may be embodied in various forms and in the illustrated form shown the brassière includes a back section 5 and a front section secured thereto along a generally vertical line 6. It will, of course, be understood that the brassière may be either a front, side or rear opening type. The brassière preferably includes a waist band 7 to fit about the waist of the wearer and to which are secured the lower edges of the rear and front sections constituting the body portion of the brassière.

The front section includes breast pockets and since such breast pockets are duplicates of each other a description of one will suffice for both.

Each breast pocket is so formed as to provide a substantial pocket with a generally horizontally extending lower supporting portion and an upper breast covering portion. The front sections may be formed of separate gores secured to each other or the material may be tucked so as to, in effect, form gored sections to provide the desired form of breast pocket. In the form illustrated each breast pocket section includes a lower piece of material 8, which may be provided with a tapering tuck 9 at each side and above that tapering tucks 10, the tapers of the tucks being such that they are wider at the rear where they join the vertical seam line 6 than at the front. These tucks and the formation of the upper edge 11 of the lower pocket section are such that the tucks, in effect, provide tapering gores with their wider portions at the rear and their narrower portions at the front, so as to form and shape the breast pocket. In the form shown the upper or breast covering portion of each pocket is formed of a separate piece of material 12, cut in generally arcuate form at the bottom so as to fit the upper arcuate edge 11 of the section 8 along the seam line 13. The breast pocket thus formed either by stitching gores together or by employing tucks in one or more pieces of material is a breast pocket which preferably has an adequately projecting or generally horizontally extending lower supporting portion 14 and an upper contour designated generally 15, which simply covers the upper portion of the breast without undue pressure thereon.

In order to assist in providing a breast pocket with a generally horizontally extending lower supporting portion as at 14, such lower section is preferably provided with gathers, as indicated generally at 16, and such gathers are preferably formed by Shirring the lower central portion 17 of the pocket section 8. The shirring is preferably done with elastic thread, so that the section 17 is laterally extensible to some extent. The gathering in or shirring of the section 17, it will be plain, provides a larger and more extensive pocket section above the shirring and the lateral extensibility of the shirred section provides for a resilient yet adequate support for the breast. The shirred section 17, which in some cases could be replaced by a separate piece of elastic material, forms a relatively stiffened portion which serves to adequately support the breast from below in the breast pocket.

In Figs. 1 and 4 of the drawing only the extreme upper part of the stiffening section is

shown as extending outwardly, as at 18, for supporting the underneath portion of the breast. However, with heavier breasts the stiffened section 17 may curve outwardly (at a considerably lower point than as shown in the drawing) to give added support. In fact, in extreme cases, the supporting section 17 might start to curve outwardly under the influence of the breast weight at a point, say, half-way down the section 17 or possibly even lower.

The brassière may be formed of any suitable material such as the materials of which brassières are now usually made. In the illustrated form the two breast pocket portions are joined at the front to a central vertical panel 19, but it will be clear that the panel 19 could be omitted and the front sections joined directly to each other. Shoulder straps have been illustrated but the use of such straps is optional, since the brassière is designed to adequately support the heavy breasts without the aid of the usual shoulder straps. It will be apparent that with the breast sections formed as described and connected to the rear section 5, pockets will be formed which will support the breasts from below without the need for shoulder straps and without any injurious pressure.

In some cases it may be desirable to provide a shirred portion at the top of each breast pocket to give a little more support, but as stated above the brassière as shown has proven entirely satisfactory.

My improved brassière is particularly advantageous when worn by a woman having extremely heavy breasts which require support from beneath and without undue pressure thereon.

While the brassière is particularly advantageous as a surgical brassière, it is advantageous for general wear by women having very heavy breasts requiring support from beneath and without undue pressure.

My improved brassière tends to enhance the beauty of the figure along natural lines and yet without any harmful pressure on the breast, such as is often occasioned by ordinary brassières worn by very heavy women.

While the invention has been described in considerable detail and a preferred form illustrated, it is to be understood that various changes and

modifications may be made within the scope of the invention as defined in the appended claims.

I claim:

1. In a garment of the character indicated, 5 front panels to cover the breasts, the upper part of each front panel being made to include a substantial breast pocket, the lower part of each front panel being shirred at the zone just beneath each breast pocket, the lower part of the 10 breast pocket and the upper part of said shirred zone merging integrally without a seam to provide a fullness in the lower part of the breast pocket, said shirred zone further providing a stiffening area directly beneath the breast pocket 15 extending substantially to the waist line of the garment.

2. In a garment of the character indicated, 20 front panels to cover the breasts, the upper part of each front panel being made to include a substantial breast pocket, the lower part of each front panel being shirred with generally horizontally extending rows of elastic thread stitches at the zone just beneath each breast pocket and 25 downwardly therefrom to provide a zone integral with the breast pocket, extending substantially to the waist line of the garment, the upper part of said zone merging with the lower part of the breast pocket, thereby providing resilient expansibility in the lower portion of the breast 30 pocket and also an integral stiffening means to assist in supporting the breasts.

3. A garment of the character indicated, 35 including a waist band, a pair of front panels to cover the breasts, the upper part of each front panel being made to include a breast pocket the bottom of which is vertically spaced from said waist band, the lower edges of said front panels being stitched to said waist band, the lower part of said front panels at the zone between said 40 waist band and vertically spaced breast pocket and generally beneath the latter being shirred, said shirred zone extending substantially to the waist band, to provide vertical stiffness for supporting the breasts and to provide a fullness in the breast pocket, the lower part of the breast merging into the upper part of the shirred zone 45 without a seam.

AGNES A. CLARK.
